REFRIGERATING APPARATUS

James W. Jacobs, Dayton, Ohio, assignor to
General Motors Corporation, Dayton, Ohio, a
corporation of Delaware

Application November 23, 1938, Serial No. 242,016

15 Claims. (Cl. 62—108.5)

This invention relates to refrigeration and particularly to freezing apparatuses such as ice trays and grids therefor employed in household refrigerators.

5 An object of the present invention is to provide an improved liquid freezing apparatus or device and a novel method of removing the device from a freezing compartment of a refrigerating system and of harvesting ice blocks from the device.

10 Another object of my invention is to utilize the force applied to a metal tray of a freezing device to break the bond between same and its support in or on a cooling element of a refrigerating system to break the bond between walls of

15 the tray and ice contained therein and to also move certain walls of a grid structure positioned in the tray relative to certain other walls thereof to liberate ice blocks from the grid structure.

20 Still another object of my invention is to stop the upward movement of a tray relative to its support at a predetermined point to twist the tray, which twisting causes a portion of the top edge of the tray to engage a part of the grid structure disposed therein and move certain of the grid walls relative to certain others thereof for liberating ice blocks from the grid structure prior to moving the tray from a cooling element to thereafter facilitate removal of the grid structure and ice blocks from the tray.

25 Further objects and advantages of the present invention will be apparent from the following description, reference being had to the accompanying drawings, wherein a preferred form of 30 the present invention is clearly shown.

35 In the drawings:

Fig. 1 is a horizontal section through a cooling element of a household refrigerator showing in plan view a freezing apparatus or device constructed in accordance with the present invention associated with the cooling element;

40 Fig. 2 is a vertical section of the freezing device taken on the line 2—2 of Fig. 1 showing an ice tray with a grid structure positioned there-
45 in;

Fig. 3 is a vertical sectional view taken on the line 3—3 of Fig. 2 illustrating the normal position of the freezing device relative to stops provided on the cooling element and adapted to be en-
50 gaged by the device;

Fig. 4 is a view showing the freezing device elevated relative to its support in or on the cooling element and showing the tray of the device in engagement with stops;

55 Fig. 5 is a view partly in section and partly in

elevation showing the tray of the device twisted by force applied thereto while engaging the stops on the cooling element, which twisting causes elevation of a part of the grid relative to another part thereof for releasing ice blocks 5 therefrom;

Fig. 6 is a sectional view taken on the line 6—6 of Fig. 5 more clearly illustrating the twisting of the tray and elevation of certain of the grid walls relative to said other grid walls; and 10

Fig. 7 is a view showing the grid structure removed from the tray of the freezing device with ice blocks released therefrom and located in the tray.

Referring to the drawings, for illustrating the present invention, I have shown in Fig. 1 there-of an evaporator or cooling element 12 of a refrigerating system which element is normally mounted in a food storage compartment of a refrigerator cabinet to cool and cause circulation of air within the compartment. The evaporator or cooling element 12 may be of any suitable or desirable construction and is preferably of the sheet metal type wherein refrigerant conveying and evaporating passages 14 are formed 25 between double sheet metal walls 15 and 16 and wherein the walls form a sharp freezing chamber 17 which is protected by the walls from air circulating within the food compartment. A liquid freezing apparatus or device, generally 30 represented by the reference character 18, and comprising a resilient thin metallic walled tray 19, having a unitary metallic grid structure 20 disposed therein, is positioned in the chamber 17 of evaporator 12. Ordinarily, the freezing of 35 liquids in an apparatus or device of the type disclosed causes the metal tray 19 to become bonded to its support and causes ice frozen within the tray to be bonded to the tray walls and to walls of the grid structure. My invention contemplates 40 the provision of an improved device wherein all three of these ice bonds can be quickly and easily broken prior to removing the freezing device from its support in a sharp freezing chamber to thereby facilitate removal of the device from the 45 freezing chamber, removal of the grid structure from the tray and harvesting of ice blocks from the tray. In carrying out this contemplation, I propose to utilize the force applied to the tray to release the device from its support, to break the 50 bond between ice in the tray and the tray walls and to also move certain walls of the grid structure relative to other walls thereof for liberating ice blocks from the grid as will be more fully described hereinafter.

The evaporator or cooling element 12 in the present invention differs from conventional evaporators of this type only in that stops are provided within the sharp freezing chamber thereof in a manner and for a purpose as will herein be described. The inner metal sheet 15 of the double metal walls at the bottom of evaporator 12 forms a flat refrigerated sharp freezing support 21 for the device or apparatus 18. Located in fixed relation with respect to and at a predetermined distance above the support 21 (see Fig. 3) there is provided a pair of stud elements 22 and 23. Each of these stud elements 22 and 23 pass through an upright wall of evaporator 12 and are riveted, welded or otherwise rigidly secured thereto. The stud elements 22 and 23 are disposed on diagonally opposite sides of the device 18 so as to locate the one stud element 22 near the rear of chamber 17 and the other element 23 at the front of the chamber 17 (see Fig. 1). Elements 22 and 23 project inwardly of the upright side walls of evaporator 12 so as to be in the path of elevation of device 18 relative to its support 21 and are thereby adapted to be engaged by tray 19 for a purpose to be hereinafter more fully explained.

The metal tray 19 of device 18 in the present invention includes side walls 26 (see Fig. 3), a bottom wall 27, and opposed end walls 28 and 29. The tray side and front end walls 26 and 28 respectively may be slightly diverged outwardly toward the top of the tray to facilitate removal of ice therefrom. The rear wall 29 of tray 19 is diverged outwardly toward the top of the tray at a greater angle than other walls thereof to permit movement of ice blocks within the tray as will hereinafter be described. The upright walls 26, 28 and 29 of tray 19 have their upper portion rolled or bent over as at 31 to provide a rim which extends around the top of the tray. A portion of the metal of tray 19 is extended downwardly, as at 32 (see Figs. 2 and 4), at the front of the tray and as at 33 at the back of the tray to form mountings for certain elements carried by the tray. A heavy metal piece 34 is mounted by screws 35 upon the downwardly directed part 32 at the front of tray 19 and has a handle 36, provided with legs 37 and 38 (see Figs. 1 and 5), pivotally secured thereto as by pins 39 or the like. The one leg 37 of handle 36 has a cam portion 41 provided thereon and the other leg 38 of handle 36 has a pin 42 secured thereto. A rod 43 secured to handle 36 by pin 42 on the leg side 38 thereof extends to the rear end of tray 19. A heavy metal piece 45 is mounted by screws 46 upon the downwardly directed part 33 at the rear of tray 19 and has a member 47 pivotally secured thereto as by pin 48. Member 47 has a cam portion 49 provided thereon for cooperation with the cam portion 41 or leg 37 of handle 36. Member 47 also carries a pin 51 to which the rear end of rod 43 is secured so that operation of handle 36 to actuate cam 41 also actuates the cam portion 49 of member 47 at the rear of tray 19. Tray 19 has a part of its front end wall 28 bulged inwardly as at 55 and is furthermore provided at its rear end 29 with a small lever 56 secured to the rim 31 of tray 19 by a pin or the like 57. The cam 41 on leg 37 of handle 36 is shaped to normally engage the support 21, while the tray 19 is positioned thereon, and maintain handle or lever 36 in an easily accessible upright position to be grasped by the hand. It is to be noted that the cam 41 engages 75 the support 21 at a point opposite the pin stop

23 and that cam 49 on member 47 engages the support 21 on the opposite side of tray 19 and at a point opposite the pin stop 22 to thereby cause a lifting action of the tray relative to its support beginning at diagonally opposite corners 5 of the tray to thus lift the tray from its support. While the rim 31 and portions 32 and 33 of metal tray 19 increase the structural rigidity of the tray the metal thereof is sufficiently resilient to permit freezing of walls thereof to elevate same 10 relative to its support and to permit twisting of the tray in a manner and for a purpose to be hereinafter described.

The unitary metallic grid structure, generally represented by the reference character 20, disposed within tray 19 of device 18 includes walls which divide the interior of the tray into a plurality of rows of cells or compartments 60. The grid 20 comprises a vertically disposed rigid metal wall or longitudinal partition 61 and a plurality 20 of spaced apart rigid metal walls 63 extending continuously through the plane of and transversely to longitudinal wall 61 and are movably connected or interlocked with wall 61. It is to be noted that grid walls 63 are normally inclined 25 or disposed at an acute angle with respect to the bottom 27 of tray 19 to provide the ice block compartments 60 with a parallelogram shape in at least one direction of cross section therethrough. Also included as a part of the unitary 30 grid structure 20 is a horizontally disposed relatively flat rigid metal member 64 which is located above and extends lengthwise with the longitudinal grid wall 61. This member 64 has a pair of legs 66 depending from each end thereof 35 and is also provided with a plurality of spaced apart elongated openings 67 (see Fig. 1) in its face. The openings 67 in member 64 receive an upwardly extended portion 68, which is bent over at 69, of each transverse grid wall 63. Openings 67 are slightly wider than the thickness of the metal extension 68 of walls 63 so as to permit tilting of these walls as will hereinafter be described. The member 64 is further provided with outwardly extending arms or wings 71 at each 45 end thereof and which arms or wings overlap the sides of tray 19 and are bent downwardly of the main body portion of member 64 to engage the tray rim 31. A pin 72 is secured to the pair of legs 66 at each end of member 64 and this 50 pin 72 extends through a vertically inclined elongated opening 73 formed in raised end portions 74 of the longitudinal grid wall 61. The connection of member 64 with grid wall 61 and the connection of transverse walls 63 with member 64 55 interlocks the various parts of the grid together to form the unitary structure 20 and also permits elevation of member 64 and walls 63 relative to grid wall 61 in a manner to hereinafter be more fully described.

Referring again to the drawings and particularly to Figs. 2 and 7, it will be noted that the longitudinal grid wall 61 is provided at one end with a notch 81 in the vicinity of the raised part 74 thereof and with a cut-out portion 82 in the 65 vicinity of the raised part 74 at the other end thereof. When the grid structure 20 is located within tray 19 the notch 81 receives the inwardly bulged part 55 of the front wall 28 of tray 19 and the cut-out portion 82 of wall 61 is engaged 70 by the finger end portion of lever 56 to hold the grid 20 within the tray and to normally prevent elevation of the longitudinal grid wall 61 relative to the tray 19. Thus the grid 20 is normally maintained in an ice block forming position within

tray 19 but the construction and cooperation of the notch 81 with the bulged portion 55 and of lever 56 with cut-out portion 82 are such that the grid 20 may be bodily removed from the tray 19.

In order to provide for the extension of grid walls 63 transversely through the plane of longitudinal wall 61, I cut a slot 85 in each wall 63 (see Fig. 3). It will be noted that the slot 85 extends upwardly from the bottom edge of walls 63 to provide a web portion 86 in these walls immediately below the upwardly extending portion 68 thereof. To accommodate the web 86 of walls 63 within the plane of longitudinal grid wall 61, I cut a plurality of slots 87 in wall 61 in spaced apart relation along the length thereof (see Figs. 2 and 7). Slots 87 extend at an angle downwardly from the top edge of wall 61 and are wider at their upper open end than at their lower closed end to permit the cross walls 63 to swing or tilt from their normal inclined position into substantially a vertical position when elevated along with member 64 relative to grid wall 61 as will become apparent in the description of operation of the device. The slots 87 thereby provide longitudinal grid wall 61 with a plurality of web portions below the slots 87 which are received in the slots 85 of transverse walls 63. While the normally inclined transverse walls 63 are equally spaced apart along member 64, the slots 87 in longitudinal wall 61 are of progressively increased width from one end to the other end of the grid structure 20. The purpose of the progressively increased width of slots 87 is to cause movement of the transverse grid walls 63 lengthwise of a longitudinal wall to be progressive from one end to the other end of the grid structure. This progressive movement of walls 63 greatly reduces the force required to move same by movement of rigid member 64 to break the ice bond between the walls 63 and ice blocks within the tray. The progressive movement of grid walls 63 thereby sequentially releases ice blocks from the grid walls and from compartments 60 to reduce the force required to operate the present device.

Assume that water has been frozen in the freezing device 18 in the form of ice blocks 90 in the compartments 60 by the refrigerating effect produced by the cooling element or evaporator 12 and removal or harvesting of these ice blocks is desired. The tray handle 36 is grasped by the hand and pulled outwardly, thus causing same to pivot about its pivotal mountings 39 and move downwardly. This initial downward movement of handle 36 causes the cam surface 41 thereon to bear against the evaporator support 21 and also causes movement of rod 43 and member 47 about its pivotal mounting 51 to thereby cause cam portion 49 of member 47 to bear against the support 21. Force thereafter applied to handle 36 and transmitted to the two cams 41 and 49 causes these cams to elevate the freezing device 18 relative to its support 21 as shown in Fig. 4 of the drawings to break the ice bond therebetween. This elevation of device 18 causes the top of the side walls of tray 19 to strike the pins 22 and 23 which pins thereby stop elevation of the tray. Continued force applied to handle 36 causes twisting of the tray 19, due to the diagonally opposite position of the stops 22 and 23, within the freezing chamber 17 prior to removing the device 18 from the evaporator 12. This twisting of tray 19 breaks the bond between ice contained in the

tray and the tray walls. Twisting of tray 19 of device 18 in the manner illustrated in Figs. 5 and 6 of the drawings also elevates diagonally opposite corners of the tray 19 above the stop pins 22 and 23, and this elevation of the tray 19 corners causes the wings or arms 71 on member 64 to be elevated. Since the longitudinal wall 61 of grid 20 is secured within tray 19, by lever 56 and bulged portion 55, against elevation relative to the tray or along with member 64 of grid 20, member 64 is raised relative to wall 61 to thereby also elevate the cross grid walls 63. It is to be noted that since walls 63 of the grid 20 are normally inclined the upward movement of member 64 relative to longitudinal grid wall 61, afforded by the vertically elongated openings 73 in wall 61, causes the transverse walls 63 to progressively engage and bear against the righthand uppermost wall portion of the inclined slots 87 during upward movement thereof. Engagement of cross walls 63 with the righthand wall of slots 87 during their upward movement with rigid member 64 causes these cross walls 63 to move relative to one another and to longitudinal grid wall 61 in another direction in addition to their elevating movement or longitudinally of the longitudinal grid wall 61. It will be noted by reference to Fig. 5 of the drawings that the normally inclined cross walls 63 have been moved out of their normal position of inclination into a more vertical position by the force imparted to member 64 through tray 19 and by movement of lever 36. The abutment of grid walls 63 with the upper portion of the righthand wall of slots 87 during elevation of walls 63 relative to longitudinal grid wall 61 simultaneously moves the lower portion of cross walls 63 lengthwise or longitudinally of grid wall 61 or into the position shown in Fig. 5. The inclination of the end wall 29 of tray 19 permits the end ice blocks to be moved upwardly by movement of the first from the rear end cross wall 63 to thereby permit movement of the next succeeding cross wall 63 and the ice blocks adjacent thereto. This progressive lengthwise movement of cross walls 63 as described breaks the bond between the ice blocks 90 and the grid walls 61 and 63 and also enlarges the ice block compartments 60 to cause the loosened ice blocks 90 to be liberated from the grid structure 20 whereupon the ice blocks freely fall into tray 19. As stated, all movements of the grid walls and liberation of the ice blocks takes place prior to removing the freezing device 18 from its freezing chamber 17 of evaporator 12.

After the tray 19 has been twisted and walls 63 of the grid moved in the manner described to liberate ice blocks 90 from the grid 20 the freezing device 18 is removed from chamber 17 of evaporator 12 and lever 56 is turned about its pivotal mounting pin 57 throughout substantially 90° from the position thereof shown in Fig. 1. Turning of lever 56 moves its finger end away from the cut-away portion 82 of longitudinal grid wall 61 to permit the unitary grid structure 20 to be removed from tray 19 of the device 18. In order to carry out removal of grid 20 from the tray to facilitate the harvesting of ice blocks from tray 19, the rear end of grid wall 61 is elevated relative to the tray and this wall is then moved toward the rear of the tray to free the portion thereof below notch 81 from the bulged part 55 of tray 19. The entire unitary grid structure 20 can then be elevated relative to the tray 19 as shown in Fig. 7 of the drawings.

From the foregoing, it will be apparent that I

have provided an improved freezing apparatus or device for refrigerating systems and have provided a novel method of operating same to facilitate the harvesting of ice blocks. In my invention I utilize a force applied to a single member for breaking a bond between a freezing tray and its support, for breaking the bond between ice in the tray and the tray walls and for also moving certain walls of a rigid walled grid structure relative to certain other walls thereof to liberate ice blocks from the grid. Therefore, my invention accomplishes in one operation and with a force applied in one direction to a single member what has heretofore had to be carried out by two or more separate members and operation of these members in a plurality of directions. My improved device is less confusing, simple in operation and practical to carry out various steps in the art of harvesting ice blocks from freezing 20 devices.

While the form of embodiment of the invention as herein disclosed, constitutes a preferred form, it is to be understood that other forms might be adopted, all coming within the scope 25 of the claims which follow.

What is claimed is as follows:

1. A refrigerating apparatus comprising in combination, a cooling element, a resilient metallic tray adapted to contain a substance to be frozen by the refrigerating effect produced by said cooling element, a grid within said tray including a longitudinal wall and a plurality of walls disposed in spaced apart relation along the length of said longitudinal wall and extending outwardly from the sides thereof to divide the interior of said tray into rows of ice block compartments, said grid also including a member disposed above said longitudinal wall and having a part thereof extending over the top of said tray 40 at the sides thereof, said member, said longitudinal wall and said plurality of outwardly extending walls of said grid being connected together in movable relation to one another to provide a unitary grid structure, means movably mounted on said tray engaging the longitudinal wall of said grid structure to normally secure said grid in said tray and to prevent movement of said longitudinal grid wall relative to the tray, a support associated with said cooling element 45 for supporting said tray, means movably mounted upon said tray and adapted to engage said support for imparting force to said tray to elevate same relative to its support, means disposed in the path of elevation of said tray, said last named means being fixed relative to said support and adapted to be engaged by said tray for stopping the elevation thereof, said last named means also being arranged with respect to the point of imparting force to said tray to cause the force, upon engagement of the tray with said means, to twist said tray, said part of said grid member being engaged by said tray upon twisting thereof for elevating said member relative to said longitudinal grid wall, said connection between said plurality of outwardly extending grid walls and said member being such that said walls are elevated along with said member upwardly of said longitudinal grid wall, said outwardly extending grid walls being interlocked with said longitudinal grid wall in such manner as to be moved relative to one another, during elevation thereof with said member, in another 45 direction of movement relative to said longitudinal grid wall other than said elevating movement thereof to break ice blocks therefrom and cause their liberation from said grid structure, and said first named means being disengageable 50 from said longitudinal grid wall to permit removal of said unitary grid structure from said tray for facilitating the harvesting of ice blocks.
2. The combination in accordance with claim 2 wherein the movement of the outwardly extending grid walls relative to one another and in a direction other than said elevating movement relative to said longitudinal wall is progressive from one portion to another portion of said grid structure.
3. A refrigerating apparatus comprising in combination, a cooling element, a resilient metallic tray adapted to contain a substance to be frozen by the refrigerating effect produced by said cooling element, a grid within said tray including a non-flexible longitudinal metal wall and a plurality of non-flexible metal walls disposed in spaced apart relation along the length of said longitudinal wall and extending outwardly from the sides thereof to divide the interior of said tray into rows of ice block compartments, said grid also including a rigid member disposed above said longitudinal wall and having a part thereof extending over the top of said tray at the sides thereof, said member,

combination, a cooling element, a resilient metallic tray adapted to contain a substance to be frozen by the refrigerating effect produced by said cooling element, a grid within said tray including a longitudinal wall and a plurality of walls disposed in spaced part relation along the length of said longitudinal wall and extending outwardly from the sides thereof to divide the interior of said tray into rows of ice block compartments, said grid also including a member disposed above said longitudinal wall and having a part thereof extending over the top of said tray at the sides thereof, said member, said longitudinal wall and said plurality of outwardly extending walls of said grid being connected together in movable relation to one another to provide a unitary grid structure, means movably mounted on said tray engaging the longitudinal wall of said grid structure to normally secure said grid in said tray and to prevent movement of said longitudinal grid wall relative to the tray, a support associated with said cooling element for supporting said tray, means movably mounted upon said tray and adapted to engage said support for imparting force to said tray to elevate same relative to its support, means disposed in the path of elevation of said tray, said last named means being fixed relative to said support and adapted to be engaged by said tray for stopping the elevation thereof, said last named means also being arranged with respect to the point of imparting force to said tray to cause the force, upon engagement of the tray with said means, to twist said tray, said part of said grid member being engaged by said tray upon twisting thereof for elevating said member relative to said longitudinal grid wall, said connection between said plurality of outwardly extending grid walls and said member being such that said walls are elevated along with said member upwardly of said longitudinal grid wall, said outwardly extending grid walls being interlocked with said longitudinal grid wall in such manner as to be moved relative to one another, during elevation thereof with said member, in another 45 direction of movement relative to said longitudinal grid wall other than said elevating movement thereof to break ice blocks therefrom and cause their liberation from said grid structure, and said first named means being disengageable 50 from said longitudinal grid wall to permit removal of said unitary grid structure from said tray for facilitating the harvesting of ice blocks.

4. A refrigerating apparatus comprising in combination, a cooling element, a resilient metallic tray adapted to contain a substance to be frozen by the refrigerating effect produced by said cooling element, a grid within said tray including a non-flexible longitudinal metal wall and a plurality of non-flexible metal walls disposed in spaced apart relation along the length of said longitudinal wall and extending outwardly from the sides thereof to divide the interior of said tray into rows of ice block compartments, said grid also including a rigid member disposed above said longitudinal wall and having a part thereof extending over the top of said tray at the sides thereof, said member,

- said longitudinal wall and said plurality of outwardly extending walls of said grid being connected together in movable relation to one another to provide a unitary grid structure, means 5 movably mounted on said tray engaging the longitudinal wall of said grid structure to normally secure said grid in said tray and to prevent movement of said longitudinal grid wall relative to the tray, a support associated with said cooling element for supporting said tray, means movably mounted upon said tray and adapted to engage said support for imparting force to said tray to elevate same relative to its support, means disposed in the path of elevation of said tray, 10 15 said last named means being fixed relative to said support and adapted to be engaged by said tray for stopping the elevation thereof, said last named means also being arranged with respect to the point of imparting force to said tray to cause the force, upon engagement of the tray with said means, to twist said tray, said part of said grid member being engaged by said tray upon twisting thereof for elevating said member relative to said longitudinal grid wall, said connection between 20 25 said plurality of outwardly extending non-flexible metal grid walls and said rigid member being such that said plurality of walls are elevated along with said member upwardly of said longitudinal grid wall, said outwardly extending grid walls being interlocked with said longitudinal grid wall in such manner as to engage same during elevation of said walls by said member to also move said outwardly extending walls relative to one another in a direction longitudinally of said longitudinal grid wall to break ice blocks therefrom and cause their liberation 10 15 20 from the grid structure, and said first named means being disengageable from said longitudinal grid wall to permit removal of said unitary grid structure from said tray for facilitating the harvesting of ice blocks. 15
7. The combination in accordance with claim 6 wherein the movement of the outwardly extending grid walls relative to one another and longitudinally of said longitudinal grid wall is progressive from one portion to another portion of said grid structure. 20
8. A freezing apparatus of a refrigerating system comprising in combination, a cooling element, a resilient metallic tray positioned on said cooling element and having a grid disposed therein, 25 said grid including a non-flexible longitudinal metal wall and a plurality of nonflexible metal walls extending continuously through the plane of said longitudinal wall outwardly from its sides to divide the interior of said tray into rows 30 of ice block compartments, said grid also including a rigid member disposed above said longitudinal wall and having a part thereof extending over the top of said tray at the sides thereof, said member, said longitudinal wall and said plurality of outwardly extending walls being connected together in movable relation to one another to provide a unitary grid structure, means for locking said longitudinal wall to said tray to prevent movement therebetween and to 35 normally secure said grid structure within the tray, means for flexing said tray to break the bond between the tray and its support on said cooling element and to twist said tray relative to said grid structure therein, said part of said grid member being engaged by said tray upon twisting thereof for elevating said member relative to said longitudinal grid wall, said connection between said plurality of walls and said rigid member being such that said plurality of 40 45 50 walls are elevated along with said member upwardly of said longitudinal grid wall, to break ice blocks therefrom and cause their liberation from said grid structure, and said first named means being disengageable from said longitudinal grid wall to permit removal of said unitary grid structure from said tray for facilitating the harvesting of ice blocks. 55
6. A freezing apparatus of a refrigerating system comprising in combination, a cooling element, a resilient metallic tray positioned on said cooling element and having a grid disposed therein, 55 said grid including a non-flexible longitudinal metal wall and a plurality of nonflexible metal walls extending continuously through the plane of said longitudinal wall outwardly from its sides to divide the interior of said tray into rows of ice block compartments, said grid also including a rigid member disposed above said longitudinal wall and having a part thereof extending over the top of said tray at the sides thereof, said member, said longitudinal wall and said plurality of outwardly extending walls being connected together in movable relation to one another to provide a unitary grid structure, 60 means for locking said longitudinal wall to said tray to prevent movement therebetween and to normally secure said grid structure within the tray, means for flexing said tray to break the bond between the tray and its support on said cooling element and to twist said tray relative to said grid structure therein, said part of said grid member being engaged by said tray upon twisting thereof for elevating said member relative to said longitudinal grid wall, said connection between said plurality of walls and said rigid 65 70 75 member being such that said plurality of walls are elevated along with said member upwardly of said longitudinal grid wall, said outwardly extending grid walls being interlocked with said longitudinal grid wall in such manner as to engage same during elevation of said walls by said member to also move said outwardly extending walls relative to one another in a direction longitudinally of said longitudinal grid wall to break ice blocks therefrom and cause their liberation 10 15 20 from the grid structure, and said first named means being disengageable from said longitudinal grid wall to permit removal of said unitary grid structure from said tray for facilitating the harvesting of ice blocks. 15
9. A refrigerating apparatus comprising in combination, a cooling member having a freezing device supported thereon, said freezing device including a tray member and a grid structure disposed in said tray member, said grid structure comprising a plurality of rigid metal walls dividing the interior of said tray member into a plurality of ice block compartments, certain of the walls of said grid structure being movable relative to a certain other wall thereof, means connected to said certain of the grid walls and extending over a top edge of said tray, means movably mounted on one of said members and adapted to engage the other of said members for imparting force between said members to elevate the tray member relative to its support on said cooling member, means fixed relative to the sup- 75

port on said cooling member and disposed in the path of elevation of said tray member for engagement thereby to stop the elevation thereof, said fixed means being arranged with respect to the point of imparting force between said members to cause the force, upon engagement of the tray member with said fixed means, to twist said tray member, said first named means being engaged by said tray member upon twisting thereof to thereby elevate said first named means relative to said tray member, and the connection of said first named means with said certain grid walls being such that the elevation of said first named means causes movement of said certain grid walls relative to said certain other grid wall to break ice blocks loose from the grid structure.

10. The combination in accordance with claim 9 wherein the movement of said certain grid walls relative to said certain other grid wall is progressive from one portion to another portion of said grid structure.

11. A liquid freezing device comprising in combination, a resilient metal tray, a grid disposed within said tray and including a plurality of rigid metal walls dividing the interior thereof into a plurality of ice block compartments, certain of the walls of said grid structure being movable relative to a certain other wall thereof, a member connected to said certain of the grid walls and having a portion thereof extending over a part of said tray, means associated with said tray and being constructed and arranged to cause twisting thereof upon application of force thereto, said member being engaged by a part of said tray and elevated relative thereto by the twisting thereof, and the connection of said member with said certain grid walls being such that the elevation of said member causes movement of said certain grid walls relative to said certain other grid wall to break ice blocks loose from their compartment walls.

12. A liquid freezing device comprising in combination, a resilient metal tray, a grid disposed within said tray including a rigid longitudinal wall and a plurality of transversely extending rigid walls disposed in spaced apart relation along the length of said longitudinal wall to divide the interior of said tray into rows of ice block compartments, said grid also including a member disposed above said walls and having a portion thereof extending over a part of said tray, said member, said longitudinal wall and said plurality of transverse walls being connected together in movable relation to one another to provide a unitary grid structure, means associated with said tray and being constructed and arranged to cause twisting thereof upon application of force thereto, said member being engaged by a part of said tray and elevated relative to said longitudinal grid wall by the twisting of said tray, said connection between said member and said longitudinal grid wall being such that said transverse walls are elevated along with said member upwardly of said longitudinal grid wall, said transverse grid walls being interlocked with said longitudinal grid wall in such manner as to be moved relative thereto progressively from one portion to another portion of said grid structure, during elevation thereof with said member, toward the vertical to enlarge said compartments and to break ice blocks loose from their compartment walls.

13. A liquid freezing device comprising in combination, a resilient metal tray, a grid disposed within said tray including a rigid longitudinal grid wall and a plurality of transversely extending rigid walls disposed in spaced apart relation along the length of said longitudinal grid wall and inclined with respect to the vertical to divide the interior of said tray into rows of ice block compartments having a parallelogram form in at least one direction of cross section therethrough, said grid also including a member disposed above said walls and having a portion thereof extending over a part of said tray, said member, said longitudinal grid wall and said plurality of transverse grid walls being connected together in movable relation to one another to provide a unitary grid structure, means associated with said tray and being constructed and arranged to cause twisting thereof upon application of force thereto, said member being engaged by a part of said tray and elevated relative to said longitudinal grid wall by the twisting of said tray, said connection between said member and said longitudinal grid wall being such that said transverse grid walls are elevated along with said member upwardly of said longitudinal grid wall, said transverse grid walls being interlocked with said longitudinal grid wall in such manner as to be moved relative thereto during elevation thereof with said member, in another direction of movement other than said elevating movement thereof to break ice blocks loose from their compartment walls.

14. A liquid freezing device comprising in combination, a resilient metal tray, a grid disposed within said tray including a rigid longitudinal grid wall and a plurality of transversely extending rigid walls disposed in spaced apart relation along the length of said longitudinal grid wall and inclined with respect to the vertical to divide the interior of said tray into rows of ice block compartments having a parallelogram form in at least one direction of cross section therethrough, said grid also including a member disposed above said walls and having a portion thereof extending over a part of said tray, said member, said longitudinal grid wall and said plurality of transverse grid walls being connected together in movable relation to one another to provide a unitary grid structure, means associated with said tray and being constructed and arranged to cause twisting thereof upon application of force thereto, said member being engaged by a part of said tray and elevated relative to said longitudinal grid wall by the twisting of said tray, said connection between said member and said longitudinal grid wall being such that said transverse grid walls are elevated along with said member upwardly of said longitudinal grid wall, said transverse grid walls being interlocked with said longitudinal grid wall in such manner as to be moved relative thereto progressively from one portion to another portion of said grid structure, during elevation thereof with said member, toward the vertical to enlarge said compartments and to break ice blocks loose from their compartment walls.

15. A liquid freezing device comprising a resilient tray, a removable unitary grid structure within said tray and including relatively movable substantially non-flexible intersecting walls forming ice block compartments, means for flexing said tray, and means responsive to said flexing operation for causing movement of said intersecting walls relative to one another to release the ice blocks from said compartments.

16. A liquid freezing device comprising a resilient metal tray, a removable unitary grid structure within said tray and including relatively movable substantially non-flexible metal intersecting walls forming ice block compartments, means associated with said tray and being constructed and arranged to cause flexing thereof, and means cooperating with said tray and grid and responsive to the flexing of said tray for moving said intersecting walls relative to one another to release the ice blocks from said compartments.

JAMES W. JACOBS.
